SHEET METAL SEAMING MACHINE

Andrew Zahner and Leo W. Zahner,
Kansas City, Mo.

Application September 16, 1937, Serial No. 164,169

8 Claims. (Cl. 113—55)

Our invention relates to improvements in sheet metal seaming machines, particularly well adapted for double seaming together the edges of metal roofing sheets.

5 One object of our invention is the provision of a novel machine of the kind described which has novel power operated means for bending the edges of side by side flanges of the metal sheets to first form a single seam, and then to form 10 therefrom a double seam.

Another object of our invention is the provision of a novel machine of the kind described which may be made to travel in one direction to form a single seam, and then backed in the opposite 15 direction to form the double seam, or which may be operated with one end as the front end in the forming of both the single and double seams consecutively.

Still another object of our invention is the provision of a machine of the kind described, which is simple, strong, durable, not likely to get out of order, which is economical in operation, will perform its work rapidly, and which is efficient in its 20 operation.

25 The novel features of our invention are herein-after fully described and claimed.

In the accompanying drawings, which illustrate the preferred embodiment of our invention;

Fig. 1 is an elevation looking at one side of our 30 improved machine, parts being broken away, showing the supporting means for the seam forming means in the initial higher position, the seam forming means being shown operatively engaging the flanges in forming a single seam.

35 Fig. 2 is a bottom view of the machine with the parts disposed as in Fig. 1.

Fig. 3 is a top view of the machine, with the parts disposed as shown in Fig. 1.

Fig. 4 is a section on the line 4—4 of Fig. 1, 40 with parts broken away.

Fig. 5 is an elevation, parts being broken away, looking at the side opposite to that shown in Fig. 1, and with the adjustable supporting means in the lower position, and the seam forming means 45 engaging the single seamed flanges in the formation of a double seam.

Fig. 6 is an enlarged section on the line 6—6 of Fig. 1.

Fig. 7 is an enlarged section on the line 7—7 of 50 Fig. 1.

Fig. 8 is an enlarged elevation of the two rear seam forming wheels shown closing the single seam, the metal sheets being shown in cross section.

55 Fig. 9 is a view similar to Fig. 8, showing the

two front seam forming wheels engaging the single seamed flanges and bending the latter laterally.

Fig. 10 is an enlarged elevation of the intermediate seam forming wheel bending the flanges 5 downwardly from their position as shown in Fig. 9, the flanges being shown in cross section.

Fig. 11 is a view similar to Fig. 8, showing the two rear seam forming wheels completing the 10 double seam.

Fig. 12 is a reduced front elevation of the upper part of one end of the adjustable frame and one of the lifting handles carried thereon.

Similar characters of reference designate similar parts in the different views. 15

The machine is provided with a traveling carrier comprising as shown a horizontal rectangular frame 1, preferably composed of angle iron, and supported by four carrying wheels 2 adapted to travel on sheet metal roofing sheets 3 and 4, 20 having respectively side by side flanges 5 and 6 of different height adapted to be seamed together by the machine, the flange 6 being the higher one.

Affixed respectively to opposite ends of the 25 frame 1 are two guiding wheels 7 and 8, which are adapted to travel on the sheet 4 closely adjacent to the flange 6. Attached to the end of the frame 1 to which is affixed the guiding wheel 8 is a cable 9 by which the machine may be 30 drawn upwardly after having traveled downwardly in a seaming operation on a roof.

In the seaming together of the flanges 5 and 6, the upper protruding part of the flange 6 is first bent laterally over the flange 5, as shown in Fig. 35 6. The bent portion 10 is then bent downwardly to an inclined position, as in Fig. 7, after which the bent portion 10 is bent against the flange 5 to form the single seam. The seamed flanges are then bent laterally and upwardly, as shown 40 in Fig. 9, then downwardly to an inclined position, as shown in Fig. 10, and finally against the flange 5 to form the double seam.

For effecting the different seaming operations just described, the following described mechanism is provided. 45

Vertically adjustable supporting means is provided consisting of two vertical end members 11 and 12 integral respectively with the ends of a longitudinal horizontal member 13 disposed in 50 an elevated position spaced from the lower ends of the members 11 and 12, which are disposed between the longitudinal sides of the frame 1 between which the supporting means is adjustable vertically and longitudinally horizontally. 55

For supporting the adjustable frame, comprising the members 11, 12 and 13, the lower ends of the vertical end members 11 and 12 have depending side edge arms 14, each having projecting laterally therefrom a horizontal supporting pin 15. The pins 15 respectively extend through and are slidably in four forwardly and upwardly inclined parallel slots 16, two of which are provided in each longitudinal side of the carrier frame 1, Figs. 1 and 5, respectively adjacent to the ends of the carrier frame 1.

The adjustable supporting frame 11, 12 and 13 is retained in the initial higher position shown in Fig. 1 by two screws 17, respectively rotatably fitted in threaded holes in the end of the frame 1 to which are attached the cable 9 and the guiding wheel 8, which screws 17 respectively abut at their forward ends against the adjacent ends of two longitudinal horizontal plates 18 and 19, Fig. 2, disposed edge to edge and fastened to the under sides of the members 11 and 12 by bolts 20. The bolts 20 which extend through the plate 18 are respectively extended through transverse slots 21, Fig. 2, whereby the plate 18 can slide laterally edgewise, a short distance, toward and from the plate 19, to accommodate the seaming means to different thickness of sheet metal plates that are being seamed, as will be afterwards explained.

30 By adjusting the screws 17 rearwardly, the weight of the supporting frame 11, 12 and 13 and the parts carried thereby will cause the supporting frame to slide downwardly and rearwardly to the position shown in Fig. 5, which is the double seaming position, the parts as shown in Fig. 1 being the single seam forming position. Screwing the screws 17 forwardly will force the supporting frame forwardly and upwardly to the higher single seaming position, shown in Fig. 1.

40 For normally yieldingly forcing the plate 18 toward the plate 19, two bolts 22 extend transversely through the plates 18 and 19, Figs. 1, 2 and 6, the heads of the bolts bearing against the outer longitudinal edge of the plate 18. Encircling the other ends respectively of the bolts 22 are two coiled compression springs 23, one set of ends of which bear against the outer longitudinal edge of the plate 19, the other set of ends bearing respectively against two washers 24 on the bolts 22, said washers respectively bearing against the nuts 25 mounted on the bolts 22. The tension of the springs 23 normally draws the plate 18 toward the plate 19.

55 The following described seaming means carried by the vertically adjustable frame 11, 12 and 13 is provided.

Rotatably mounted at their upper ends in the member 13 of the supporting frame are two vertical shafts 26 which extend downwardly through the plate 19 and have respectively fastened to them circular disks or forming wheels 27, which are respectively adjacent to and cooperate with two forming wheels 28, respectively fastened to two vertical rotary shafts 29, which extend upwardly through the plate 18 and are rotatably mounted at their upper ends in the member 13, Figs. 1, 2, 4, 5 and 6.

70 The forming wheels 28 have upwardly and outwardly beveled portions 30 which respectively extend laterally over the peripheries of the forming wheels 27, each of which is adapted to engage and bend laterally the portion 10 of the flange 6, as shown in Fig. 6, when such of the two wheels is in advance and the carrier frame 1 is operatively moved. In such case the other set of

forming wheels 27 and 28 is engaged in closing the single seam, as in Fig. 8, after the bent portion 10 has been bent downwardly from the inclined position, shown in Fig. 6 to the downwardly inclined position shown in Fig. 7.

5 For turning down the upper portion 10 of the flange 6 from the upwardly inclined position shown in Fig. 6, an intermediate peripherally grooved forming wheel 31 is rotatably mounted on a short transverse horizontal bar or shaft 32, 10 mounted at its ends in transverse aligned holes 33 provided in the inner longitudinal edges of the plates 18 and 19, Fig. 7. The shaft 32 and forming wheel 31 are located midway between the two sets of forming wheels 27 and 28. The peripheral 15 groove 34 provided in the forming wheel 31 is provided with an outwardly inclined circular wall 35 which in operation is disposed at the side of the flanges 5 and 6, as to be adapted to engage the upwardly inclined portion 10, and bend it 20 downwardly to the position shown in Fig. 7, after which the following set of wheels 27 and 28 engage the bent portion 10 and forces it against the flange 5 so as to close the single seam, as shown in Fig. 8.

25 Respectively fastened to the shafts 26 above the plate 19 are two spur gear wheels 36 which respectively mesh with two spur gear wheels 37 secured to the shafts 29, Figs. 4 and 6. For revolving the shafts 26 simultaneously in the 30 same direction, said shafts have respectively fastened on them two sprocket wheels 38, Figs. 1, 4 and 5, connected by a chain belt 39, which also engages with a sprocket wheel 40 fastened on a vertical shaft 41 below the member 13 through 35 which the shaft 41 extends. For rotating the shaft 41 it has fastened to it above the member 13 a bevel gear wheel 42 which meshes with two bevel gear wheels 43 and 44, which are rotatable on a longitudinal shaft 45, rotatably mounted 40 in two bearings 46 mounted on the member 13.

The shaft 45 extends through the end member 11 and has fastened on it a spur gear wheel 47 which meshes with a smaller spur gear wheel 48, which is fastened on a longitudinal armature 45 shaft 48 of an electric motor 50 mounted on the member 13.

50 It will be obvious that any usual type of motor or engine, as a gasoline motor, could be substituted for the electric motor 50, for driving the shaft 49.

To enable the shaft 45 rotating selectively the bevel gear wheels 43 and 44, so as to reverse the direction of rotation of the shaft 41, and that of the shafts 26, a clutch is provided, which consists 55 of a sleeve 51, Figs. 1 and 3 splined to and longitudinally slidably on the shaft 45. The sleeve 51 is provided in its end respectively with two recesses 52 and 53 adapted to respectively receive selectively two studs 54 and 55 with which the 60 adjacent ends of the bevel gear wheels 43 and 44 are provided.

65 As shown in Figs. 1 and 3, the stud 55 of the gear 44 is in the recess 53 of the sleeve 51. In such position of the parts, if the shaft 49 is rotated by the motor 50 in the direction indicated by the adjacent arrow in Fig. 1, the chain belt 39 will be driven in the direction indicated by the adjacent arrow in Fig. 1, which will be the proper direction for it to travel, when the machine 70 travels to the left, as shown in Fig. 1.

75 Such direction of drive will cause the forming wheels 27 and 28 of each set will travel in opposite directions and will have proper traveling engagement with the flanges 5 and 6, when the 75

left end of the machine, as shown in Fig. 1, is the front end.

In case it is desired to have the machine operated with the other end as the front end, that is the right end, as viewed in Fig. 1, means are provided for shifting the sleeve 51 so that it will have driving engagement with the gear wheel 43, such means consisting of a hand lever 56 pivoted on a pin 57 mounted in and extending upwardly from the member 13, Fig. 3. The lever 56 has in it a pin 58 disposed in a peripheral groove 59 in the sleeve 51, by which the sleeve is shifted into either of its two operative positions.

When the lever 56 is swung to move the sleeve 51 to the left, as viewed in Fig. 1, into engagement with the gear wheel 43, the latter will be rotated by the sleeve, and will drive the gear 42 in a direction the reverse that in which it was driven by the gear wheel 44, thereby reversing the rotation of the shafts 41 and 26 and the forming wheels 27 and 28, so that the latter will have proper traveling engagement with the flanges 5 and 6, when the machine travels to the right, as viewed in Fig. 1, and the member 12 is at the front.

In Figs. 1 and 5, the member 11 is at the front, and the lever 56 is then positioned, as shown in Fig. 3, with the gear 44 operatively engaged with the sleeve 51.

For lifting the machine, four bars 60 are respectively fastened to the vertical edges of the members 11 and 13, and extend upwardly from said members, as shown in Figs. 1 and 12. A cylindrical transverse bar 61 is fastened at its ends to and between the bars 60 attached to the member 11, and a similar bar 61 is similarly fastened to and between the bars 60 attached to the member 12. The bars 61 serve as handles by which the machine may be lifted and carried.

An easy way of operating the machine is to dispose it on a roof with the parts disposed, as in Fig. 1, with the member 11 at the front, and let the machine travel down the roof by gravity, it being held back to a proper rate of travel by the cable 9.

The front guiding wheel 7 and the rear guiding wheel 8 are disposed closely adjacent to the flange 6 at the side opposite that to which the upper part 10 of the flange 6 is to be bent.

As the machine travels downwardly the bevelled portion 30 of the front forming wheel 28 bends the upper part 10 of the flange laterally over the flange 5, as shown in Fig. 6.

As the machine progresses, the inclined wall 35 of the intermediate forming wheel 31, bends the part 10 downwardly to the position, shown in Fig. 7. The rear wheels 27 and 28 then fold the part 10 against the flange 5, thus closing the single seam, as shown in Fig. 8.

The machine is then drawn upwardly by the cable 9 to the initial position, and the screws 17 are rearwardly adjusted to permit the supporting frame 11, 12 and 13 to lower by gravity to the lower rear position, shown in Fig. 5.

The machine is then positioned to engage the single seam which has just been formed disposed between the front forming wheels 27 and 28. When the machine travels downwardly, the front wheels 27 and 28 will bend laterally, as shown in Fig. 9, the upper portions of the flanges 5 and 6. As the machine progresses, the intermediate wheel 31 will bend the flanges 5 and 6 downwardly, as shown in Fig. 10, following which the rear forming wheels 27 and 28 will close and

form the double seam, as shown in Fig. 11, and in Fig. 5.

If desired, after the single seam has been formed, as described, the machine may be drawn upwardly by the cable 9 to form the double seam, 5 by backing up the machine. In such case, the lever 56 is swung to engage the sleeve 51 with the gear 43, thus reversing, as has been described, the direction of rotation of the forming wheels 27 and 28, so that they have proper traveling 10 engagement with the flanges 5 and 6. After the double seam has been formed, the supporting frame is adjusted to the higher position, as has been described, and the lever 56 is swung to re-engage the sleeve 51 with the gear 44, following 15 which another single seam is formed, in the manner described.

As shown in Figs. 1, 2 and 5, for guiding the upwardly inclined portion 10 of the flange 6 against the inclined wall 35 of the wheel 31, two 20 guiding rollers 62, of like diameter and with longitudinally aligned axes, are rotatably mounted on two plates 63 fastened to the under side of the plate 19, the peripheries of said rollers being substantially in longitudinal alignment 25 with the inner edge of the inclined wall 35 of the intermediate forming wheel 31, the rollers being disposed respectively at the front and rear of the wheel 31.

As the flanges 5 and 6 enter between the forming wheels 27 and 28, they push the wheels apart, and force the plate 18 away from the plate 19 against the tension of the springs 23. The springs 23 permit the forming rollers to be relatively properly positioned with different thicknesses of metal plate that is to be seamed.

By having the wheels 27 and 28 of one pair corresponding in shape and relative disposition to each other to the wheels 27 and 28 of the other pair, the carrier may be operated in reverse 40 directions without being reversed, thus affording a saving in time and labor.

To enable the wheels 27 and 28 being reversed in rotation to adapt them to the carrier being operated in such reverse directions, without being reversed end to end, the reversing mechanism hereinbefore described is provided.

While the screws 11 are provided for releasably holding the vertically adjustable frame in the upper position, when making a single seam, 50 the weight of said frame and the motor and parts carried thereby, combined with the inclination or slant given the slots 16, serve to retain the frame in the lowered position, shown in Fig. 5, when the carrier is either drawn upwardly or let 55 downwardly on a slanting roof to make a double seam. Furthermore, the front wheel 27 engaging the underside of the seam 10, Fig. 9, holds the frame down in the slots 16, even on relatively steep roofs. Of course, the machine need not 60 be used on roofs having a pitch such that would reverse the inclination of the slots 16.

Many modifications of our invention, within the scope of the appended claims, may be made without departing from the spirit of our invention.

What we claim is:

1. In an apparatus of the kind described, a carrier adapted for travel parallel with two side by side flanges of different height, of two roofing sheets, supporting means on said carrier, two rotary wheels on said supporting means adapted to embrace and have traveling engagement with opposite sides of said flanges, said wheel engaging the higher of said flanges having means, 70

- when said carrier travels parallel with said flanges, for bending the upper part of the higher flange laterally over the other flange, means on said supporting means at the rear of said two 5 wheels for engaging and bending downwardly said bent part, and two rotary wheels on said supporting means at the rear of said last named means adapted to engage said bent flange at opposite sides of said flanges and bend said bent 10 part against the other flange to form a single seam, said two rear wheels corresponding in shape and relative disposition to each other to said two first named wheels respectively, whereby said carrier may be operated in reverse directions without being reversed. 15
2. In an apparatus of the kind described, a carrier adapted for travel parallel with two side by side flanges of different height, of two roofing sheets, supporting means on said carrier, two 20 rotary wheels on said supporting means adapted to embrace and have traveling engagement with opposite sides of said flanges, said wheel engaging the higher of said flanges having means, when said carrier travels parallel with said flanges, for bending the upper part of the higher flange laterally over the other flange, an intermediate rotary wheel on said supporting means at the rear of said two wheels having means for 25 engaging and bending downwardly said bent part, and two rotary wheels on said supporting means at the rear of said intermediate wheel adapted to embrace opposite sides of said flanges, one of said last named wheels having means for engaging said bent part and folding it downwardly and against the other flange to form a single seam, said two rear wheels corresponding in shape and relative disposition to each other to said two first 30 named wheels respectively, whereby said carrier may be operated in reverse directions without being reversed. 35
3. In an apparatus of the kind described, a carrier adapted for travel parallel with two side by side flanges of different height, of two roofing sheets, supporting means adjustable on said 40 carrier from a higher initial position to a lower position, two rotary wheels on said supporting means adapted to embrace and have traveling engagement with opposite sides of said flanges, said wheel having engagement with the higher of said flanges, when said carrier travels parallel with said flanges, and said supporting means is in said initial higher position, engaging and bending laterally the upper part of said higher flange, intermediate means on said supporting 45 means at the rear of said two wheels engaging and bending downwardly said bent portion, and two rotary wheels on said supporting means at the rear of said intermediate means adapted to embrace opposite sides of said flanges, one of 50 said last named wheels having means for engaging said bent part and folding it downwardly against the other flange, when in said initial position, to form a single seam, said first named two wheels, when in said lower position, and 55 said carrier travels parallel with said flanges, being adapted to embrace said seamed flanges and bend them laterally, said intermediate means, when in said lower position, being adapted to engage and bend downwardly said bent flanges, said rear two wheels, when in said lower position and said carrier travels parallel with said flanges, being adapted to embrace and bend said bent flanges against each other to form a double seam, said two rear wheels corresponding in shape and relative disposition to each 60
- other to said two first named wheels respectively, whereby said carrier may be operated in reverse directions without being reversed. 65
4. In an apparatus of the kind described, a carrier adapted for travel parallel with two side by side flanges of different height, of two roofing sheets, supporting means on said carrier adjustable from a higher initial position to a lower position, two front rotary wheels on said supporting means, two rear rotary wheels on said supporting means, a rotary wheel on said supporting means intermediate of said two pairs of wheels, said front wheels in said higher initial position being adapted to engage and bend laterally over the other flange the upper part of the higher flange, when said carrier travels parallel with said flanges, said intermediate wheel being adapted to engage and bend downwardly said bent part, and said rear wheels being adapted to embrace opposite sides of said flanges and, in said initial position bend said bent part against the other flange to form a single seam, said front wheels in said lower position being adapted to embrace said seamed flanges and bend them laterally, said intermediate wheel in said lower position being adapted to engage and bend downwardly said bent flanges, said rear wheels in said lower position, being adapted to embrace and bend said bent flanges to form a double seam, and means for oppositely rotating the wheels of each of said pairs in directions such that they will have each forward traveling engagement with the flanges which they respectively engage, said two rear wheels corresponding in shape and relative disposition to each other to said two first named wheels respectively, whereby said carrier may be operated in reverse directions without being reversed. 70
5. In an apparatus of the kind described, a carrier adapted for travel parallel with two side by side flanges of different height, of two roofing sheets, supporting means on said carrier, two front rotary wheels on said supporting means, two rear rotary wheels on said supporting means, a rotary wheel on said supporting means intermediate of said two pairs of wheels, said front wheels being adapted, when said carrier travels parallel with said flanges, to embrace opposite sides of said flanges and to bend laterally the upper part of said higher flange over the lower flange, said intermediate wheel being adapted to engage and bend downwardly said bent part, said rear wheels being adapted to embrace said flanges and bend said bent part against the other flange to form a single seam, and means for oppositely rotating the wheels of each of said pairs in directions such that they will each have forward traveling engagement with the flanges which they respectively engage, said two rear wheels corresponding in shape and relative disposition to each other to said two first named wheels respectively, whereby said carrier may be operated in reverse directions without being reversed. 75
6. In an apparatus of the kind described, a carrier adapted for travel forwardly and backwardly parallel with two side by side flanges of different height, of two roofing sheets, supporting means on said carrier, two rotary front wheels on said supporting means, two rear rotary wheels on said supporting means corresponding in shape and relative disposition to each other to said two front wheels respectively, a rotary wheel on said supporting means intermediate of said two pairs of wheels, said front wheels having means by which, when said carrier travels paral-

lel with said flanges they embrace and have traveling engagement with opposite sides of said flanges and bend laterally the upper part of said higher flange over the other flange, said intermediate wheel having means for engaging and bending downwardly said bent part, said rear wheels having means by which they embrace and have traveling engagement with said flanges and bend said bent part against the other flange to form a single seam, means for oppositely rotating the wheels of each pair, and means for reversing the direction of rotation of said rotating means, whereby either end of said carrier may be the front end.

15. In an apparatus of the kind described, a carrier adapted for travel parallel with two side by side flanges, of different height, of two roofing sheets, said carrier being adapted for travel in reverse directions without being reversed, two longitudinally aligned flange folding means on said carrier, each of which when it is at the front being adapted to engage and bend the upper part of the higher flange laterally over the other flange, and means intermediate of said two flange folding means for engaging and bending downwardly said bent part, each of said two flange folding means when it is at the rear being adapted to engage said downwardly bent part and bend it against said other flange to form a single seam.

30. In an apparatus of the kind described, a carrier adapted for travel parallel with two side by side flanges, of different height, of two roof-

ing sheets, said carrier being adapted for travel in reverse directions without being reversed, supporting means on said carrier adjustable from a higher position to a lower position, two longitudinally aligned flange folding means on said supporting means, each of which when it is at the front and said supporting means is in said upper position being adapted to engage and bend the upper part of the higher flange laterally over the other flange, and means carried by said supporting means intermediate of said two flange forming means for engaging and bending downwardly the part bent laterally by said front flange folding means, each of said two flange folding means when it is at the rear and said supporting means is in said upper position being adapted to engage and bend downwardly bent part against the other flange to form a single seam, each of said two flange folding means when it is at the front and said supporting means is in said lower position being adapted to engage and bend laterally said seamed flanges, said intermediate means, when said supporting means is in said lower position being adapted to engage and bend downwardly said laterally bent seamed flanges, each of said two flange folding means, when at the rear, and said supporting means is in said lower position, being adapted to engage and bend said downwardly bent seamed flanges against said other flange to form a double seam.

ANDREW ZAHNER.
LEO W. ZAHNER.
